[57] CLAIM

The ornamental design for an electric fence extender
for T-posts, substantially as shown.

DESCRIPTION

FIG. 1 is a top plan view of an electric fence extender
for T-posts embodying our new design;

FIG. 2 is a bottom plan view thereof;

FIG. 3 is a front elevational view;

FIG. 4 is a rear elevational view;

FIG. 5 is an end elevational view taken from the right in
FIG. 3, and

FIG. 6 is an end elevational view taken from the left in
FIG. 3.
